Patented Nov. 30, 1915.

Fig. 4.

UNITED STATES PATENT OFFICE.

THOMAS A. HOOKEY, OF McDONALD, PENNSYLVANIA.

RAIL-JOINT.

1,162,609.

Specification of Letters Patent. Patented Nov. 30, 1915.

Application filed July 9, 1915. Serial No. 38,932.

To all whom it may concern:

Be it known that I, THOMAS A. HOOKEY, a citizen of the United States, residing at McDonald, in the county of Washington and State of Pennsylvania, have invented new and useful Improvements in Rail-Joints, of which the following is a specification.

This invention relates to certain new and useful improvements in rail joints, and the invention has for its object to provide a novel rail chair to which the confronting ends of two sections of rails can be easily and quickly clamped.

15 A further object of the invention is to provide a rail joint that shall prevent the lateral and vertical displacement of the rails and to permit of only a limited longitudinal movement of the said rails.

20 With the above and other objects in view, the improvement resides in the construction, combination and arrangement of parts set forth in the following specification and falling within the scope of the appended claim.

25 In the drawing: Figure 1 is a perspective view of my improved joint. Fig. 2 is a cross section of the same. Fig. 3 is a perspective view of the chair or base of the improvement, and Fig. 4 is a similar view of the removable side or fish plate.

30 The rail joint is composed of two elements, a chair 1 and a fish plate 2, both of which are adapted to embrace rails 3 and 4 and to be secured together by the usual spikes which are arranged to contact with the longitudinal edges of the rails and which enter the supporting ties.

35 The chair 1 comprises a base or rail receiving seat 5 having integrally formed therewith, at a suitable distance from one of its longitudinal edges, an inwardly extending angular flange 6 which terminates in a vertical plate 7, the flange 6 and the plate 7 providing a fish plate, the inner surface 40 of which conforming to one of the sides of the rails and the upper edge of the plate 7 underlying and contacting with the heads of said rails. This plate 7 upon its inner face is formed with laterally extending 45 studs 8, and these studs enter the bolt openings in the webs of the rails 3 and 4. The opposite longitudinal edge of the plate is provided with a vertical extension 9, the inner face of which being beveled from its 50 upper to its lower edge and the said mem-

ber 9 is of a greater width at one of its ends than at its opposite end.

Formed integral with the base 5, and disposed a suitable distance from the plate or extension 9 is a second plate 10, the opposite longitudinal edges of the same being beveled inwardly from top to bottom thereof, so that the said plate is substantially dovetailed shape in cross section and the side or edge of the plate disposed adjacent the beveled and inclined inner face of the plate 9 is spaced from the said plate 9 a greater distance at one of its ends than at its other end, thus providing a substantially dovetailed channel 11 between the said plates 9 and 10, which gradually decreases in width from one of the ends thereof to the opposite end. The plate 10 also is of a greater width at one end than at the other end, so that the said plate provides what may be termed a wedge-shaped member.

55 The base 5 adjacent the plate 10 is provided with spike openings 13—13, the said spike openings being so arranged as to have their inner walls disposed in a line with one of the longitudinal edges of the rails 3 and 4, and the flange 6 as well as the base plate are likewise provided with openings 14, and these openings are also adapted for the reception of securing spikes, and the same 60 may be so disposed as to communicate with one of the longitudinal edges of the base flanges of the rails, so that the spikes passing through the same will contact with the said rails.

65 The fish plate 2 has its horizontal flange 15 upon its inner edge beveled, as at 16, to conform to the shape of the base flanges of the rails upon which it is adapted to rest. Thus the flange 15 is of a greater thickness 70 than the vertical plate 17 of the fish plate, and this thickened portion, which is disposed to the rear of the beveled surface 16, is channeled longitudinally, as at 18, and the opposite walls of the channel are beveled from their lower edges to the top wall 75 providing a substantially dove-tail shaped channel and the said channel is wider at one end than at its opposite end, thus conforming to the shape of the plate 10, with 80 which it is adapted to engage. The flange 15 at the outer edge thereof is also channeled longitudinally, and the inner wall of 85 said channel, indicated by the numeral 20, is beveled and inclined to agree with the 90

95

100

105

110

shape of the upper wall of the dove tailed channel 11, within which it is adapted to be received and thus it will be noted that the lower face of the horizontal portion of the 5 fish plate is formed with tongues and grooves which alternate with the tongues and grooves provided by the plates 9 and 10 of the chair 1 and the space between the inner inclined wall of the member 10 and the said 10 tongues and grooves is of a wedge-shaped formation, so that the greater the distance the fish plate 2 is moved upon the base of the chair, the tighter the vertical plate as well as the base flange engaging portion 16 15 of the said fish plate 2 will contact with the rails. The portion 16 is provided with openings 25 which are adapted to be brought into register with the openings 13, and the securing spikes, heretofore referred to, are 20 passed through such alining openings to effectively lock the fish plate 2 upon the base of the chair member 1 and to thus provide a strong and effective joint.

From the above description, taken in connection with the accompanying drawing, the simplicity of the device, as well as the advantages thereof will, it is thought, be perfectly apparent to those skilled in the art to which such invention appertains without 30 further detailed description.

Having thus described the invention, what I claim is:

A rail joint comprising a base portion having an integral fish plate, the vertical 35 member of the fish plate being integrally formed with lateral studs which are adapted to be received in the bolt openings of rails when the said rails are arranged upon the base, the longitudinal edge of said plate opposite the fish plate being formed with an 40 integral upwardly extending plate, the inner wall of which being beveled and the said inner wall being inclined from one of its

ends to its opposite end, a second plate which is dove-tailed in cross section, formed 45 integral upon the base and disposed away from the first mentioned plate, the said plate being of a greater width at one of its ends than at its opposite end, providing a substantially dove-tailed passage between both 50 of the said plates, a removable fish plate having a thickened base channeled at its outer longitudinal edge and at a distance away from the said longitudinal edge to provide a dove-tail shaped tongue which is 55 of a greater width at one of its ends than at its opposite end, the inner wall provided by the inner channel being beveled or inclined to correspond with the inner wall of the tongue and thus providing a dove-tail 60 shaped channel, the tongue adapted to be received in the channel between the upstanding plates upon the base and to frictionally engage with the walls thereof, the inner beveled wall of the inner channel of the base 65 of the fish plate engaging with the inner beveled wall of the inner plate upon the base of the chair, the horizontal member of the fish plate and the base of the chair being formed with spike receiving openings arranged to aline with the longitudinal edges 70 of the rails, securing members passing through said openings, the horizontal member of the fish plate being formed with spike openings which aline with openings in 75 the base of said chair, said openings being disposed to aline with one of the longitudinal edges of the rails, and spikes passing through said openings and contacting with the said rails.

In testimony whereof I affix my signature in presence of two witnesses.

THOMAS A. HOOKEY.
